(57) **CLAIM**

The ornamental design for a finger brace, as shown and described.

DESCRIPTION

FIG. 1 is a front perspective view of a finger brace, showing our new design.

FIG. 2 is a front perspective view of a second embodiment of a finger brace.

FIG. 3 is a left side elevational view of the finger brace of FIG. 1.

FIG. 4 is a right side elevational view thereof.

FIG. 5 is a front elevational view thereof.

FIG. 6 is a rear elevational view thereof.

FIG. 7 is a top plan view thereof; and,

FIG. 8 is a bottom plan view thereof.

In the drawings, the broken lines show portions of a human finger that forms no part of the claim.
